United States Patent

Des. 239,382
Patented Mar. 30, 1976

239,382

BUILDING

Anthony P. Moscatelli, 239 N. Queens Ave.,
Massapequa, N.Y. 11758

Filed July 31, 1974, Ser. No. 493,606

Term of patent 14 years

Int. Cl. D25—03

U.S. Cl. D13—1 F

FIG. 1

FIG. 1 is a front perspective view of a building incorporating my new design.

FIG. 2 is a top plan view thereof.

The end opposite the end shown in FIG. 1 is identical to the view illustrated. The bottom and rear are plain, having no ornamental features.

I claim:

The ornamental design for a building, substantially as shown and described.
